TOY VEHICLE

Dietrich G. Rempel, Akron, Ohio, assignor to
 Rempel Manufacturing, Inc., Akron, Ohio, a
 corporation of Ohio

Application June 10, 1946, Serial No. 675,703

5 Claims. (Cl. 46—201)

1

This invention relates to toy vehicles of vulcanized rubber or the like, molded to simulate the appearance of real vehicles such as automobiles.

An object of the invention is to provide a toy vehicle having a body part of vulcanized rubber, and improved means for quickly and securely mounting a chassis therein, whereby production costs are reduced to a minimum.

Another object of the invention is to provide a rubber toy vehicle of the character described with a simple inexpensive means for mounting a propelling mechanism in the same.

These and other objects of the invention will be manifest from the following brief description and the accompanying drawings.

Of the accompanying drawings:

Figure 1 is a longitudinal cross-section through a toy automobile embodying the features of the invention.

Figure 2 is a cross-section taken substantially on the line 2—2 of Figure 1.

Figure 3 is a fragmentary cross-section taken substantially at the line 3—3 of Figure 1.

Figure 4 is a top perspective view of a chassis, including a propelling mechanism, of the type adapted to be incorporated in the toy.

Figure 5 is a view similar to Figure 3, illustrating a modified form of the invention.

Figure 6 is a fragmentary view taken substantially at the line 6—6 of Figure 5.

Figure 7 is a bottom plan view of a toy automobile, illustrating another modified form of the invention.

Figure 8 is a fragmentary cross-section taken substantially on the line 8—8 of Figure 7.

Referring particularly to Figures 1, 2, 3 and 4, the numeral 10 designates a body of a toy vehicle formed of vulcanized rubber to simulate a real automobile. The body 10 is hollow to save rubber, and may be open at the bottom to define a generally rectangular skirt portion 13, which due to the inherent resiliency of the rubber is of requisite flexibility for a purpose to be described.

Provided around the inner periphery of the rectangular skirt portion 13 may be vertically spaced ribs 15, 15, defining relatively narrow grooves 16, 16 and 16a, 16a at opposite ends and opposite sides, respectively, of the body for snugly receiving corresponding opposite end and opposite side portions 17, 17 and 17a, 17a, of substantial length, on frame 18 of a chassis 19 (see Figure 3). The frame 18 is formed of a narrow strip of relatively stiff material, such as metal, to be received in the grooves 16, 16a. At each

2

corner of frame 18 the sides are oppositely inwardly offset, as indicated at 18a, 18a, for receiving opposite rubber wheels on front and rear axles 20 and 21 mounted between said offset side portions of the frame. On rear axle 21 is a gear 23 for meshing with a gear 24 on a shaft 25, extending between the sides of the frame. For propelling the toy, the shaft 25 carries a suitable spring winding mechanism 26 adapted to be wound, by means of a key 27 shown in chain-dotted lines in Figure 4, to turn the rear wheel assembly 21 in the frame through gears 24 and 23.

In production of the toy vehicle described, the chassis 19 is assembled on the body 10 by flexing the lower skirt portion 13 outwardly, against strong inherent resiliency of the rubber thereof, substantially as indicated in chain-dotted lines in Figure 1. The frame 18 may be slightly larger than the recess 17 to assure tight gripping of the skirt portion about the frame securely and thereby retain the body and chassis in assembled relation. A suitable aperture may be provided in one side of the skirt portion 13 for receiving winding key 27 therethrough and onto the outwardly projecting shaft extension 25a of the winding mechanism. The resilient flexibility of the skirt portion 13 for the purposes described may be enhanced by provision of integral reinforcing cross-members 33 and 34 in the hollow body 10, as well as by the relative proportions of ribs 15 of the perimetrical groove 16.

The above-described construction makes possible the provision of a simple wind-up propelling mechanism for rubber toy vehicles, and the method of assembling and mounting the chassis 19 in the body 10 reduces production costs to a minimum with a consequent reduction in the cost of the finished article.

Referring particularly to Figures 5 and 6 there is illustrated a modified form of the invention, wherein integral rubber buttons 35 are provided in the skirt portion 13 at the sides thereof within a groove 16a. Each button 35 is provided with a relatively short neck portion 36 and an enlarged head 37, the rubber head being adapted to be yieldingly urged through an aperture 38 in the frame 18, of substantially the same shape and size as neck portion 36. Thus the head will engage the inner face of frame 18 to provide additional locking means for retaining the frame in position. The head 37 may be tapered inwardly of body 10 to facilitate ready reception thereof through aperture 38. One or more of the buttons 35 is provided at each side of body 10 in particular

instances where the body is relatively long and flexible.

The modified form of the invention illustrated in Figures 7 and 8 is in principle similar to that illustrated in Figures 1 to 4. The frame 40, however, is rectangular and is yieldingly received in a correspondingly rectangular groove 41 provided around the inner perimeter of the skirt portion 42 of the rubber vehicle body 43. Slots 44 are provided in the skirt portion 42 for receiving the axles 45 and 46 of the front and rear assemblies of the frame 40, and recesses 47, 47 are provided on the under side of the body 43 for receiving the wheels 48, 48. The propelling mechanism carried by the frame 40 is otherwise the same as previously described.

Other modifications of the invention may be resorted to without departing from the spirit thereof or the scope of the appended claims.

What is claimed is:

1. A toy vehicle comprising a chassis including a frame of relatively rigid construction having end portions of substantial extent along opposite portions to provide bearing surface, and a hollow body of rubber or like resilient material, said body opening at the bottom to provide a skirt portion having generally the configuration of the frame, said skirt portion having lateral grooving presented inwardly of the body corresponding to said frame portions, said frame being received in said grooving by flexure of said skirt portion and being retained therein by the inherent resiliency of the material of said body, said frame having a plurality of apertures therein and said skirt portion having integral protuberances in the grooving receivable therethrough for locking the frame in said groove.

2. A toy vehicle comprising a chassis including a frame of relatively rigid construction having opposite edge portions of substantial length, and a body of rubber or like resilient material, said body being hollow and opening at the bottom to define a flexible skirt portion having generally a configuration corresponding to said edge portions, said skirt portion having lateral grooving presented inwardly of the body, said frame edge portions being received in said grooving by flexure of said flexible skirt portion and being retained therein by the inherent resiliency of the material of said body, interengaging means being provided on said frame and said body to lock the same together.

3. A toy vehicle comprising a chassis including a frame having opposite portions of substantial length, and a body hollowed on the underside thereof to define a skirt portion of flexible resilient material and having generally the configuration of the frame, said skirt portion having

lateral grooving presented inwardly of the body corresponding to said frame portions, said frame being received in said grooving by flexure of said flexible skirt portion and being retained therein by the inherent resiliency of the material of said skirt, spaced wheel assemblies carried by said frame, one of said wheel assemblies including an axle rotatable with respect to the frame and at least one wheel thereof being driven by the rotatable axle, and a spring-wound mechanism carried by said frame and including a driving connection to said rotatable axle to rotate said driven wheel or wheels for propelling the toy.

4. A toy vehicle comprising a chassis including a frame having opposite portions of substantial length, and a body hollowed on the under side thereof, to define a skirt portion of flexible resilient material having generally the configuration of the frame, said skirt portion having lateral grooving presented inwardly of the body corresponding to said frame portions, said frame being received in said grooving by flexure of said flexible skirt portion and being retained therein by the inherent resiliency of the material of said skirt, spaced wheel assemblies carried by said frame, one of said wheel assemblies including an axle rotatable with respect to the frame and at least one wheel thereof being driven by the rotatable axle, and a propelling mechanism carried by said frame and including a driving connection to said rotatable axle to rotate said driven wheel or wheels for propelling the toy.

5. A toy vehicle comprising a chassis including a frame having opposite portions of substantial length and a body hollowed on the underside thereof, to define a skirt portion of flexible resilient material and having generally the configuration of the frame, said skirt portion having lateral grooving presented inwardly of the body corresponding to said frame portions, said frame being received in said grooving by flexure of said flexible skirt portion and being retained therein by the inherent resiliency of the material of said skirt, spaced wheel assemblies carried by said frame including axles mounted on said frame and having wheel members freely rotatable on opposite ends thereof.
